(57) **CLAIM**

The ornamental design for a pointed face of a sheet element used in construction of hollow shaped bodies, as shown and described.

DESCRIPTION

Cross-reference to Related Applications: Application Ser. Nos. 29/535,778, 29/547,983.

FIG. 1 is a front perspective view of a pointed face of a sheet element used in construction of hollow shaped bodies;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view thereof, shown in use.

The broken lines shown in the drawings illustrate portions of the pointed face of a sheet element used in construction of hollow shaped bodies that form no part of the claimed design.
